UNITED STATES PATENT OFFICE.

GEORGE LEONARD HILLS, OF FRANKLIN, ILLINOIS

AUTOMOBILE WHISTLE.

1,070,602.

specification of Letters Patent. Patented Aug. 19, 1913.

Application filed July 31, 1912. Serial No. 712,533.

To all whom it may concern:

Be it known that I, GEORGE LEONARD HILLS, a citizen of the United States, residing at Franklin, in the county of Morgan, 5 State of Illinois, have invented certain new and useful Improvements in Automobile Whistles; and I do hereby declare the following to be a full, clear, and exact description of the invention, such as will enable 10 others skilled in the art to which it appertains to make and use the same.

This invention relates to automobile alarms and has for an object to provide a novel pump actuated whistle that is 15 hingedly attached to the side of the chassis and is provided with a friction pulley which is adapted to be moved into engagement with the engine fly wheel by depression of a pedal on the foot board.

20 With the above objects in view the invention consists of certain novel details of construction and combination of parts hereinafter fully described and claimed, it being understood that various modifications 25 may be made in the minor details of construction within the scope of the appended claim.

In the accompanying drawing forming part of this specification: Figure 1 is a perspective view of the device in applied position. Fig. 2 is a vertical sectional view taken 30 on the line 2—2 Fig. 1. Fig. 3 is a horizontal sectional view through the device with parts in elevation. Fig. 4 is a vertical sectional view on the line 4—4 Fig. 2.

35 Referring now to the drawing in which like characters of reference designate similar parts, 10 designates the side of an automobile chassis, 11 the engine fly-wheel, and 40 12 the foot board.

The alarm device comprising the subject-matter of this invention consists of a leaf hinge 13 one leg of which is bolted or otherwise rigidly fixed to the side of the 45 chassis, the other leg being terminally equipped with a tubular bearing box 14 in which is revolvably mounted a shaft 15 which carries on one end a friction pulley 17 adapted to be brought into engagement with 50 the underside of the fly-wheel, the shaft being equipped on the opposite end with a

rotary pump designated in general by the numeral 18, the pump carrying a whistle 19 of ordinary character that extends rearwardly along the side of the chassis.

55 A pull rod 20 is connected at the lower end to an eye 21 carried by the free leg of the hinge, and extends in upright position toward the foot board, a pedal 22 being pivoted intermediate the ends on the foot board as shown at 23, the lower end of the pedal extending through the foot board and being pivotally connected to the upper end of the push rod by a pin 24. A helical spring 25 is interposed between the free 60 end of the pedal and the foot board and serves to normally hold the friction pulley 65 out of engagement with the engine fly-wheel. Upon depression of the pedal the pull rod 20 will be raised and will rock 70 the free leg of the hinge upwardly with a resultant engagement of the friction pulley with the fly-wheel.

75 The pump is preferably formed of a plurality of fan blades 26 which are fixed to the shaft 15, a cylindrical casing 27 housing the blades and having a tubular bearing 28 on one side housing the shaft 15 and having an air intake opening 28' on the same side. A constricted outlet nozzle 29 leads 80 from the fan casing to one end of the whistle 19. The pump casing is preferably formed integral with the free leg of the hinge. Hard oil or grease cups 30 and 31 engaged 85 through the tubular bearings of the hinge and fan casing serve to lubricate the shaft 15.

85 What is claimed, is:—

An automobile alarm device including the combination with the chassis and fly wheel 90 of an automobile, of a downwardly extending leaf hinge having one leg fixed to the chassis side, and having the free leg terminally equipped with a transverse tubular bearing, a fan casing having one side integral with the side edge of the last named leg and having a tubular bearing on the opposite side alining with the first named bearing, and further having an air intake opening on the last named side, a shaft engaged 95 through said bearings, a friction pulley on said shaft engageable with said fly wheel, 100

fan blades on said shaft housed within said fan casing, a wind instrument operatively connected to said fan casing, and means for 5 rocking said free leg and moving said friction disk into and out of engagement with said fly wheel.

In testimony whereof, I affix my signature, in presence of two witnesses.

GEORGE LEONARD HILLS.
